INDEX CARD

Joseph M. Meyers, Pittsburgh, Pa., assignor to
Remington Rand Inc., Buffalo, N. Y., a corpora-
tion of Delaware

Application August 15, 1930. Serial No. 475,537

5 Claims. (Cl. 129—16.8)

My invention refers to improvements in card index systems, and particularly to the adjustable portion of a card thereof, for identification or location of any particular portion of the card or 5 marking thereon, as a date, subject, or action indicia.

In such card systems, the cards are arranged alphabetically or otherwise in a holder or set for 10 ready examination or selection, each card containing reference information of various kinds. It is also customary to provide adjustable devices of various kinds capable of being set from time to time along the edge of the card to assist or inform the user of any particular fact, as a maturing or 15 action-taking date, relating to the information or business covered by the card.

In my invention I utilize an ordinary flat stiff paper card, in which are pressed or molded one or more longitudinal grooves, together with a 20 movably mounted indicator, slidably engaging the groove or grooves, while still having a firm normally inseparable connection laterally.

The improvement, in one preferred form, is 25 shown in the accompanying drawing, in which:—

Fig. 1 is a perspective view of a card provided with my improvement;

Fig. 2 is a vertical sectional view on the line II—II of Fig. 1;

Fig. 3 is a sectional view similar to Fig. 2 showing a modified construction;

Fig. 4 is an edge view of a blank from which the shifting indicator is formed;

Fig. 5 is an edge view of the indicator;

Fig. 6 is a face view of the same, detached;

Fig. 7 is a similar face view showing a modified construction;

Fig. 8 is a face view of a further modified construction;

Fig. 9 is an edge view of the construction of Fig. 8.

Referring to the drawing, A is an index card, similar in proportions and function to those commonly employed in many card index systems in 45 general use, adapted to be mounted or assembled in a case, drawer, or other receptacle, either vertically or horizontally, for purposes of easy inspection.

Card A is provided along one of its edges, either 50 upper or lower, with a movable or shifting indicator B, for the purpose of bringing it into register with any particular unitary data or indicia imprinted or otherwise marked along the edge of the card, as indicated, and capable of adjustment in either direction, and of firmly maintaining its

position against accidental disturbance or dislocation.

The indicator B is preferably provided with an opening 2 for exposure of a limited area of the card within such opening. The indicator itself is 60 made of a blank 3 of thin sheet metal, as copper, aluminum, celluloid, or other suitable light material, capable of being bent upon itself and of maintaining such bent or deformed position.

Blank 3 is provided at one or both ends with a 65 short lip, lug or flange 4, and the blank is bent upon itself as at 5, so as to form outer and inner parallel walls 6 and 7 respectively, with the lug or lugs 4 disposed inwardly, as in Fig. 5.

As thus formed, the indicator B is adapted to 70 be slidably mounted along the edge of card A in the manner of a clip, longitudinally adjustable as stated, and with the inwardly extending lugs 4 in embracing engagement with the opposite sides of the card.

For the purpose of providing trackways along the card, it is grooved or channelled at one or both sides, as at a, by subjecting the card to rollers or other suitable means, whereby to crease or indent it longitudinally from one end to the 80 other, in a permanent manner.

The groove or grooves a are of such a size and depth as to receive the inwardly extending lug or lugs 4 when the indicator is inserted over one end of the card, firmly gripping it with considerable friction and also providing ample holding effect against lateral displacement or removal.

In Fig. 3, I show a modification, utilizing both lugs but providing only one corresponding groove 85 for the same purpose and effect. Where but one groove is utilized, as for one or the other of the lugs, it will produce substantially the same effect, the other lug bearing frictionally against the plane surface of the card.

The construction of the indicator itself, aside from its facility of operation purely as an indicator, likewise affords an easy and convenient holding device, by which the cards may be manipulated or shifted.

When desirable to expose the full edge surface of the card the opening 2 is extended clear to the inside edge 13 of the bend 5, co-extensive with the edge of card A, as in Fig. 7.

In Figs. 8 and 9 I show a further modified construction in which the indicator is provided with a supplemental upper or outer extension 8, having a window or sight opening 9 through one or both opposite sides of the extension 8. Such extension is effected by use of an extra long blank 110

bent midway of its formation beyond location of the usual top 5, at which point the opposite sides of the blank are brought together in abutting relationship, as indicated at 10.

- 5 The construction below such point is substantially the same as that above described, and the supplemental extension 8 is formed by the spaced apart sides with the intervening space 11, the indicator being rounded or closed at the top as at 10 12, similar to the usual upper edge 5. By such construction I provide not only an extended grasping formation, but at the same time utilize the space 11 between the extended walls for insertion of a small card or other device having 15 a suitable imprint for reading or inspection through the opening 9. In case the indicator is made of celluloid, providing visibility, the opening 9 may be omitted. Otherwise the clip and its holding action and movement along the edge 20 of the card is substantially the same as already described.

I have found also that movement of the indicator along the card tends to more definitely wear and deepen the grooves *a*, and that the indicator may even be applied to a plane ungrooved card, and will by its lugs 4 form corresponding grooves.

The construction, operation, use, and advantages of the invention will be readily understood and appreciated by all those familiar with the use 30 of index cards. It is comparatively simple, cheap and effective, and greatly contributes to the usefulness and efficiency of the ordinary card index system.

35 The device may be changed or modified by the skilled mechanic as to variations in size, design, or otherwise, but all such changes are to be understood as within the scope of the following claims.

40 What I claim is:

1. In combination with an index card having oppositely located longitudinal grooves, a slideable indicator thereon having redoubled embracing side walls each having an inwardly extending lip engaging one of said grooves, one of said side walls having a sight opening.
2. In combination with an index card having an indented longitudinal groove on each of the opposite sides adjacent one margin, a slideable indicator consisting of a blank of thin sheet material bent upon itself at the top to provide a spaced-apart slot-like opening between the opposite parallel walls, one of said walls having a sight opening, the walls being brought together

55 and then formed into spaced apart parallel walls for card embracing engagement, each of said walls having an inwardly extending lip, said last named parallel walls straddling said margin of the card with said lips resiliently engaging in the grooves thereof.

80 3. In combination with an index card having an elongated groove on each of the opposite sides adjacent a common margin, a slideable indicator comprising a strip of resilient material bent upon itself to form spaced front and back walls and inwardly extending lips on the extremity of each of the walls, said indicator straddling said margin of the card with its lips resiliently engaging in corresponding slots on the card.

85 4. An index comprising a record card formed of a paper sheet, said sheet having a portion scored to provide a groove along one margin and in one face parallel to the adjacent edge, and an indicator of sheet metal formed to provide a pair of spaced wall portions of unequal length engaging opposite faces of the margin of said card, said indicator having a portion joining said wall portions beyond said edge, and a laterally inwardly directed tip on the shorter wall portion 90 substantially perpendicular to said sheet slidably engaging in said groove, said tip lying over the opposite wall portion and cooperating to normally retain said indicator on said sheet against movement other than sliding movement in said 95 groove.

100 5. An index comprising a record card formed of a paper sheet having a portion scored along one margin inwardly from the edge to provide a groove substantially parallel to said edge, and an 105 indicator formed of a strip of sheet metal having opposite ends formed to provide wall portions of unequal length arranged in spaced substantially parallel relation, an intermediate portion of the strip connecting said wall portions at one end 110 and the opposite ends terminating in offset relation, the shorter wall portion having the free end formed with a substantially perpendicular inwardly extending lip directed toward an intermediate portion of the other wall portion, said 115 lip slidably engaging in said groove and said other wall portion lying on the opposite side of the margin of said card and cooperating with the card to retain said lip in said groove, whereby 120 said indicator is slideable along the margin of said 125 card and normally retained thereon against detachment by movement laterally on said margin.
